Primary Examiner — Timothy Wilhelm

(57) **ABSTRACT**

A work machine includes a frame, a traction system, an engine, an implement system, an operator cab with a roof; a machine control system, and a secondary control system. The secondary control system is configured to interface with the machine control system and includes a secondary control device, a control module, a communication module, a base plate, and two rails. The base plate is configured to support the control module and the communication module, and protect the plurality of harness connections. The two rails are configured to support the base plate in an operation orientation and a service orientation and each include a plurality of channels configured to support the base plate in the service orientation.

**SECONDARY CONTROL SYSTEM AND
METHOD FOR MOUNTING WITH SERVICE
ORIENTATION**

TECHNICAL FIELD

The present disclosure relates generally to tractor machines, and more specifically to machines with a secondary control system.

BACKGROUND

Work machines are used for innumerable purposes across many industries. These machines includes construction machines such as motor graders, excavators, and bulldozers; farm equipment such as tractors and combines; mining equipment; cement trucks; dump trucks; garbage trucks; and the like. During the performance of tasks, the machines may operate in situations that are unsuitable or undesirable for a human operator such as hazardous conditions, extreme environmental conditions, uncomfortable for an operator, or at work locations remote from civilization. Because of these factors, the completion of some tasks by an onboard operator may be dangerous, expensive, and otherwise undesirable.

One solution is to control and operate the machines with a secondary control system. In some situations, a remote control system may be added to a machine as an after-market addition. U.S. Pat. No. 9,213,331 to Johnson describes such a remote control system.

However, many of these systems must be removed completely from the machine for maintenance, diagnostics, and other servicing. Therefore, there is a need for a method for mounting a secondary control system that allows for in-situ maintenance.

SUMMARY OF THE DISCLOSURE

According to one aspect of the present disclosure, a work machine is disclosed. The work machine includes a frame, a traction system, an engine, an implement system, an operator cab with a roof a machine control system, and a secondary control system. The secondary control system is configured to interface with the machine control system and includes a secondary control device, a control module, a communication module, a base plate, and two rails. The base plate configured to support the control module and the communication module, and protect the plurality of harness connections. The two rails are configured to support the base plate in an operation orientation and a service orientation and each include a plurality of channels configured to support the base plate in the service orientation.

According to another aspect of the present disclosure, a secondary control system is disclosed. The secondary control system includes a secondary control device configured to accept input from a remote operator, a plurality of electrical components including a secondary control module and a communications module, a base plate configured to support the plurality of components, a first rail, and a second rail. Each of the rails is configured to support the secondary control system in an operation orientation and a service orientation and includes a first flange configured to be attached to a surface, a web, a second flange, and a plurality of channels extending from the second flange into the web.

According to yet another aspect of the present disclosure, a method of moving a secondary control system into a service orientation is disclosed. The method includes providing a secondary control system with a base plate mounted

2

to two rails in an operation orientation, removing a plurality of bolts attaching the base plate to the rails, lifting the base plate and lowering the base plate into a channel on each of the two rails, the base plate being supported by the channels in a service orientation

These and other aspects of the present disclosure will be more readily understood after reading the following detailed description in conjunction with the accompanying drawings.

10 BRIEF DESCRIPTION OF THE DRAWINGS

FIG. 1 is a side view of a work machine, according to one aspect of the present disclosure.

FIG. 2 is a block diagram of a control system, according to one aspect of the present disclosure.

15 FIG. 3 is a perspective view of the cab roof of the work machine of FIG. 1, according to one aspect of the present disclosure.

FIG. 4 is a perspective view of the cab roof of the work 20 machine of FIG. 1, according to one aspect of the present disclosure.

FIG. 5 is a perspective view of a base plate, according to one aspect of the present disclosure.

25 FIG. 6 is a perspective view of a rail, according to one aspect of the present disclosure.

FIG. 7 is a perspective view of an opposite side of the rail of FIG. 6, according to one aspect of the present disclosure.

FIG. 8 is a cross-section of the rail of FIG. 6 and FIG. 7, according to one aspect of the present disclosure.

30 FIG. 9 is a perspective view of the rail and baseplate of FIGS. 5 and 6, according to one aspect of the present disclosure.

FIG. 10 is a perspective view of the rail and baseplate of FIGS. 5 and 6, according to one aspect of the present disclosure,

35 FIG. 11 is a perspective view of the baseplate of FIG. 5 being lifted by a crane.

FIG. 12 is a method of moving the baseplate of FIG. 5 between an operation orientation and a service orientation.

40 DETAILED DESCRIPTION

Reference will now be made in detail to specific embodiments or features, examples of which are illustrated in the 45 accompanying drawings. Wherever possible, corresponding or similar reference numbers will be used throughout the drawings to refer to the same or corresponding parts.

Referring now to the drawings, and with specific reference to FIG. 1, a work machine in accordance with the present disclosure is generally referred to by reference numeral 100. The work machine 100 may be any one of a number of different earth moving, construction, agricultural, or industrial machines, such as a motor grader, mining truck, bulldozer, excavator, tractor, or the like. As such, the depicted wheel loader is only one example of a possible work machine according to the present disclosure.

The work machine includes a frame 110, a propulsion system 120 mounted to the frame 110, and a traction system 130 supporting the frame 110 and driven by the propulsion system 120. The propulsion system 120 may include a power source such as a combustion engine or electric motor and a transmission. The traction system 130 may include wheels (as shown), tracks, treads, or the like which enable the work machine 100 to engage the ground and move.

60 The machine 100 may additionally have an implement system 140 supported by the frame 110. The implement system 140 may include various implements 150 attached to

the machine 100 to perform a variety of jobs. The illustrated machine 100 is equipped with a bucket 150; however, many other implements may be used on other machines to perform different types of work. Some machines 100 may include more than one implement, while others such as trucks may have no implement. A hydraulic system 160 may be utilized to drive the movement of the implement system 140.

The machine 100 also includes an operator cab 170 supported by the frame 110. The cab includes a roof 180. A top surface of the roof 185 is generally flat and parallel to the plane of the ground surface 190 below the machine 100. The operator cab 170 is configured to allow an operator to control the systems 120, 130, 140, 160 of the machine through an operator interface 210 (see FIG. 2). The operator interface 210 may include a plurality of operator input devices such as joysticks, buttons, touchscreens, steering wheel, switches, and the like, and may also include a plurality of display devices such as screens, lights, dials or other indicators of the machine's status.

In addition, the machine 100 is equipped with a plurality of sensors 220 that gather data from various components and systems and generate signals that are indicative of the performance and operating conditions of the machine 100. Sensors 220 may be associated with, for example, the propulsion system 120, the traction system 130, the operator cab 170 and interface 210, the implement system 140 and hydraulics 160, and/or other systems and components of the machine 100.

A machine control system 230 is provided to control the operation of the machine 100. As shown in FIG. 2, the machine control system 230 includes a machine control module 240 which interfaces between the plurality of sensors 220, the operator interface 210, and the various systems 120, 130, 140, 160 of the machine 100. The machine control module 240 may be configured to provide an operator with information from the sensors and control the engine 120, traction system 130, implement system 140 and other systems and components as directed by an operator through the operator interface 210. The machine control module 240 may be a single control module or include a plurality of control modules interfacing with parts of the machine.

The machine 100 may also be equipped with a secondary control system 250. The secondary control system 250 is configured to interface with the machine control system 230 and allow control of the machine 100. For example, the secondary control system 250 may allow control of the machine from the machine 100, may allow for video recording or allow for collision avoidance, may allow for machine automation, and the like. The secondary control system 250 includes a plurality of electrical components which may include a secondary control module 260, a communication module 270, a secondary control device 280, and a plurality of harnesses 290. The secondary control module 260 interfaces between the machine control module 240 and the secondary control device 280 to allow the operator to control the machine 100. The communication module 270 is configured to provide wireless communication between the secondary control module 260 and the secondary control device 280. The communication module 270 may include a plurality of transmitters and receivers. The wireless communication may be through radio, Bluetooth, an wireless network, or other similar means. The remote control device 280 includes an operator interface which may include a plurality of displays and input devices. The secondary control device 280 also includes transmitters and receivers to communication with the communication module 270. The control module 260 and the communication module 270 are

mounted on the machine, while the secondary control device 280 may be located at a distance from the machine, limited by the range of the communication method used. The plurality of harnesses 290 provide electrical connections between the machine 100 and the control 260 and communication modules 270 to provide power to the components and interface between the secondary control system 250 and the machine control system 230.

In order to allow for an efficient connection between the 10 secondary control system 250 and the machine 100, the secondary control system 250 may be located adjacent to the machine control module 240. In order to be protected from the environment and wear caused by the operation of the machine 100, the roof 180 of the cab 170 provides a suitable 15 location, but other locations are possible.

In some alternative embodiments, the secondary control system 250 may be mounted to a different surface of the machine other than the roof 180 of the operator cab 170. This machine surface should be substantially flat and parallel to a ground surface and located to allow the secondary control system 250 to interface with the machine control system 230.

In order to mount the secondary control system 250 to the roof 170 of the operator cab 170, the secondary control system 250 further includes a mounting system 300, as shown in FIGS. 3 and 4. The mounting system 300 includes a base plate 310, a first rail 320, and a second rail 330. The first rail 320 and the second rail 330 are mirror images of each other and may be described collectively as the rails 340. The rails 340 are configured to support the base plate 310 in an operation orientation (shown in FIG. 3) and a service orientation (shown in FIG. 4).

As shown in FIG. 5, the base plate 310 is made up of a large panel 410 with a lower face 415 on which components 35 including the secondary control module 260 and the communication module 270 may be mounted. The panel 410 may be rectangular with two long sides 420, and two short sides 430. On each of the short sides 430, the panel includes a mounting surface 440 extending outward parallel to the plane of the panel 410. The mounting surfaces 440 may include a plurality of mounting holes 450. On each of the long sides 420, a lip 460 extends along the length of the panel 410 perpendicularly to the lower face 415. The lip 460 provides additional protection to the secondary control module 260 and the communication module 270 in the operation orientation. On each end of each of the lips 460, a corner bracket 470 is attached. The corner brackets 470 are attached to an inner side of the lip 460 and extend around 90 degrees to the short sides 430. Two kickstands 480 may extend from an outer side of one or both lips 460. One or both of the lips 460 may also include a mechanism 490 for attaching a crane.

In one embodiment, the long sides 420 of the panel 410 may be between 1290 mm and 1500 mm, and the short sides 430 of the panel 410 may be between 50 mm and 150 mm, 55 although of course, other dimensions may be used as dictated by the size of the surface on which the remote control system is to be mounted.

As shown in FIGS. 6 and 7, each of the rails 340 is an 60 elongated beam shape with a web 510, a first flange 520, and a second flange 530. The first flange 520 is configured to be attached to the roof 180. The first flange 520 may be attached to the roof 180 by any suitable method, including bolts (as shown), screws, adhesive, and the like. The first flange 520 may include bolt holes as needed to secure the rail to the roof. The first flange 520 is connected to a first side 540 of the web 510. The web 510 extends perpendicularly from the first flange 520, away from the roof 180 when the rail 340

is mounted. The first flange 520 may extend from the web 510 in only one direction as depicted, toward the longitudinal axis of the machine 100 when mounted. Alternatively, the first flange 520 may extend from the web on both sides creating a wider area of contact with the roof.

The second flange 530 extends perpendicularly from a second side 550 of the web 510. The second flange 530 is configured to extend away from the longitudinal axis of the machine 100 when mounted. The second flange 520 of each rail 340 is configured to connect to the mounting surface 440 of the base plate 310 in order to support the base plate 310 with its mounted components in the operation orientation. Together, the first flange 520, web 510, and second flange 530 may form a Z-shape in cross-section, as shown in FIG. 8.

Each of the rails 340 also includes a plurality of channels 560. Each channel 560 extends through the second flange 530 into the web 510, perpendicular to the rail 340. A channel 560 on the first rail 320 has a corresponding channel on the second rail 330. The rails 340 have at least one channel 560 each and may have a second channel 560. The channels may be at each end of the rail. Multiple channels 560 provides options for the location of the baseplate 310 on the roof 180 when in the service orientation. Some locations may be preferred for the particular machine 100 or by a particular service provider.

The rails 340 may also include an upright tab 570 extending from the web 510 to aid in guiding the base plate 310 into place. In some embodiments, as shown, the upright 570 may be located adjacent to a channel 560.

The height of the web (H) is greater than the lip 460 of the base plate 310 plus any components that may be mounted on the lower face 415. In one embodiment, the height H may be 80 mm, but of course other dimensions may be used as needed to accommodate the required components.

The channels 560 are configured to allow the mounting surface 440 to slide within. Therefore, the width of each channel 560 must be wider than the thickness of the mounting surface 440. In some embodiments, the mounting surface 440 may have a thickness of 6 mm and the channels 560 may have a width of 9 mm, but other dimensions are possible.

The rails 340 are mounted on each side of the roof 180 (or other machine surface) and positioned to be parallel to one another. The rails 340 may also be parallel to a longitudinal axis of the machine 100. The distance between the rails 340 when mounted is configured to allow the long sides 420 of the base plate 310 to fit between the web 510 of the first and second rails 340.

When in the operation orientation, the plane of the base plate 310 is parallel to the plane of the roof 180, as shown in FIGS. 3 and 9. The mounting surfaces 440 of the base plate 310 are resting on and removably attached to the second flanges 530 and the corner brackets 470 are removably attached to the web 510 of each rail 310. The control module 260 and the communication module 270 are protected between the base plate 310 and the roof 180.

In the service orientation, the base plate 310 is perpendicular to the roof 180, as shown in FIG. 4. The mounting surface 440 is inserted into the channels 260 such that the base plate 310 stands upright (see FIG. 10). The base plate 310 may also be supported by the kickstands 480. The plurality of harnesses 290 remain connected to the machine 100 and the remote control system 250 so that maintenance can occur while the system is powered and connected.

Industrial Applicability

The present disclosure finds application for any machine with a secondary control system mounted on a roof or other machine surface. More generally, the mounting system disclosed above may be advantageous for numerous machines in which a secondary control system such was but not limited to remote control, video recording, collision avoidance and machine automation must be mounted to the outside of a machine and accessible for maintenance.

A method 600 for moving a mounted secondary control system into a service orientation is shown in FIG. 11, beginning in block 610. First, a secondary control system 250 is provided in which a base plate 310 is mounted to two rails 340 in an operation orientation (block 610). As previously described, in the operation orientation, the mounting surface 440 on each short side of the base plate 310 is attached to the second flange 530 of a rail 340 by bolts through a plurality of mounting holes 450 and the corner brackets 470 are attached to the web 510 of each rail by additional bolts. In some embodiments, there may be a total of 12 bolts, but of course other totals are possible.

In order to begin moving to the service position, all of these bolts are removed, as shown in block 620. Next, the base plate 310 is lifted and rotated (block 630). This may be done manually by an operator, or by attaching a crane to the base plate 310. The crane may be connected to the lip 460 on either long edge 420 of the base plate 310, as preferable for the particular servicing required or the arrangement of the roof 180. As the base plate 310 is lifted, it rotates into a position perpendicular to the roof 180. Finally, the base plate 310 is lowered into the channels 560 on each rail 340, as shown in block 640. Each mounting surface 440 fits within a channel so that the base plate 310 is supported in an upright position between the two rails 340. Kickstands 480 on the base plate 310 may provide additional support.

The method 600 may be reversed to return the base plate 310 to the operation orientation. During the process of moving between orientations, the secondary control system 250 does not need to be disconnected from the machine control system 230.

While the preceding text sets forth a detailed description of numerous different embodiments, it should be understood that the legal scope of protection is defined by the words of the claims set forth at the end of this patent. The detailed description is to be construed as exemplary only and does not describe every possible embodiment since describing every possible embodiment would be impractical, if not impossible. Numerous alternative embodiments could be implemented, using either current technology or technology developed after the filing date of this patent, which would still fall within the scope of the claims defining the scope of protection.

What is claimed is:

1. A work machine, comprising:
a frame;
a traction system supporting the frame;
an engine supported by the frame;
an implement system supported by the frame;
an operator cab supported by the frame, the cab having a roof;
a machine control system configured to control the traction system and implement system based on operator input; and
a secondary control system configured to interface with the machine control system, the secondary control system having:
a secondary control device,
a control module,

- a communication module,
a plurality of harness connections,
a base plate configured to support the control module
and the communication module, and protect the
plurality of harness connections, and
two rails configured to support the base plate in an
operation orientation and a service orientation, the
rails each including a plurality of channels config-
ured to support the base plate in the service orien-
tation.
2. The work machine of claim 1, wherein the base plate
is perpendicular to the roof in the service orientation.
3. The work machine of claim 1, wherein the base plate
is parallel to the roof in the operation orientation.
4. The work machine of claim 1, wherein the base plate
is a rectangular panel having:
a lower face, the lower face configured to permit mount-
ing the secondary control module and the communica-
tion module,
two long sides, the long sides having a lip extending
perpendicularly from the lower face,
two short sides, the short sides each having a mounting
surface, each mounting surface configured to be remov-
ably attached to a rail.
5. The work machine of claim 4, the base plate further
having a plurality of corner brackets attached to the lip,
configured to be removably attached to the rail.
6. The work machine of claim 1, wherein the rails each
have a first flange, a web, and a second flange, the first flange
configured to be attached to the roof of the machine, the
second flange configured to be removably attached to the
base plate.
7. The work machine of claim 6, wherein the plurality of
channels extend through the second flange into the web and
are configured to support a mounting surface of the base
plate such that the base plate is supported between the two
rails perpendicularly to the roof.
8. A secondary control system, comprising:
a secondary control device configured to accept input,
a plurality of electrical components including a secondary
control module and a communications module;
a base plate configured to support the plurality of com-
ponents;
a first rail; and
a second rail,
each of the rails configured to support the secondary
control system in an operation orientation and a service
orientation and having a first flange configured to be
attached to a surface, a web, a second flange, and a
plurality of channels extending from the second flange
into the web.
9. The secondary control system of claim 8, wherein the
base plate is perpendicular to the rails in the service orien-
tation.
10. The secondary control system of claim 8, wherein the
base plate is a rectangular panel having:
a lower face, the lower face configured to permit mount-
ing the plurality of components,
two long sides, the long sides having a lip extending
perpendicularly from the lower face,
two short sides, the short sides each having a mounting
surface.
11. The secondary control system of claim 10, wherein
each mounting surface is configured to be removably
attached to the second flange of one of the two rails.

12. The secondary control system of claim 8, wherein the
plurality of channels extend through the second flange into
the web and are configured to support a mounting surface of
the base plate such that the base plate is supported between
the two rails perpendicularly to the roof.
13. A method of moving a secondary control system into
a service orientation, comprising:
providing a secondary control system with a base plate
mounted to two rails in an operation orientation, the
rails each including a channel, a first flange, a web, and
a second flange,
the first flange configured to be attached to a surface,
the second flange configured to be removably attached
to the base plate;
removing a plurality of bolts attaching the base plate to
the rails;
lifting and rotating the base plate; and
lowering the base plate into the channel on each of the two
rails, the base plate being supported by the channels in
a service orientation, wherein the base plate is perpen-
dicular to the rails in the service orientation.
14. The method of claim 13, wherein the base plate is a
rectangular panel having:
a lower face, the lower face configured to permit mount-
ing a plurality of components;
two long sides, the long sides having a lip extending
perpendicularly from the lower face,
two short sides, the short sides having a mounting surface,
the mounting surface configured to be removably
attached to a rail.
15. The method of claim 14, the base plate further having
a plurality of corner brackets attached to the lip, configured
to be removably attached to the rail.
16. The method of claim 13, wherein the plurality of
channels extend through the second flange into the web and
are configured to support a mounting surface of the base
plate such that the base plate is supported between the two
rails perpendicularly to the surface.
17. The method of claim 13, the base plate further having
a plurality of kickstands attached to the lip, the kickstands
configured to assist in supporting the base plate in the
service orientation.
18. The method of claim 13, wherein the base plate is
lifted with a crane.
19. A method of moving a secondary control system into
a service orientation, comprising:
providing a secondary control system with a base plate
mounted to two rails in an operation orientation, the
rails each including a channel;
removing a plurality of bolts attaching the base plate to
the rails;
lifting and rotating the base plate, wherein the base plate
is lifted with a crane; and
lowering the base plate into the channel on each of the two
rails, the base plate being supported by the channels in
a service orientation, wherein the base plate is perpen-
dicular to the rails in the service orientation.
20. The method of claim 19, wherein the rails each
include a first flange, a web, and a second flange, the first
flange configured to be attached to a surface, the second
flange configured to be removably attached to the base plate.
